Wesley S. Barr
ATTORNEY

UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC CANDY-WARMING TABLE.

Application filed December 2, 1922. Serial No. 604,497.

To all whom it may concern:

Be it known that I, JAMES C. WOODSON, a citizen of the United States, and a resident of East Pittsburgh, in the county of Allegheny and State of Pennsylvania, have invented a new and useful Improvement in Electric Candy-Warming Tables, of which the following is a specification.

My invention relates to electric heating devices and particularly to electrically heated candy warmers.

The object of my invention is to provide a relatively simple, rugged and electrically-heated surface of relatively large area that shall be uniformly heated.

In practicing my invention, I provide a pair of superposed spaced sheet-metal plates having laterally extending and interengaging edge flanges. A plurality of layers of refractory heat-insulating material is located on the lower plate and supports a layer of a flexible electric-insulating material, to which is secured an electric heating element distributed substantially uniformly over the surface thereof. A layer of flexible electric-insulating material is located above the heating element, and a layer of mica is located between the top metal plate and the superposed flexible layer of electric-insulating material.

A removable cloth cover is located on the outside surface of the top metal plate, means being provided to secure the side edges thereof to the down-turned edge flanges of the top plate and further means being provided to clamp the end edge portions of the cloth cover against the edge flanges of the top plate.

In the single sheet of drawings,

Figure 1 is a fragmentary top plan view of a device embodying my invention,

Fig. 2 is a view, in vertical lateral section therethrough,

Fig. 3 is a partial longitudinal section therethrough, and

Fig. 4 is a diagrammatic representation of a heating element constituting a part of the device embodying my invention.

A bottom sheet-metal plate 11, of substantially rectangular contour, is provided, at each of its edges, with an integral upturned flange portion 12. Upon the metal plate 11 is located a layer 13 of asbestos lumber. Upon the layer 13 is located a layer 14 of asbestos paper which is of rela-

tively high heat-insulating capacity, as compared with that of the asbestos lumber employed for the layer 13.

Located upon the layer 14 is a layer 15 comprising a relatively thin sheet of woven asbestos cloth. The three layers 13, 14 and 15 are maintained in proper operative positions, relatively to each other, by means of edge strips 16, of L-shape in lateral section, extending along the side edges thereof. A plurality of flat-head machine screws 17 and co-operating nuts 18 serve to hold the members 16 against the edges of the superposed layers and also hold the three layers in close operative engagement relatively to each other.

A heating element for the device comprises a plurality of helically wound resistor members 19 extending in spaced relation longitudinally of the device. The individual resistor members are secured against the layer 15 by means of fine metal wire 21 at numerous points. A layer 22 of a heat-conducting and electric-insulating material, such as asbestos cloth, is located immediately above the resistor members 19 and has depending edge portions which extend along the upturned edge flanges of the sheet-metal plate 11. A layer 23 of mica is located immediately above the layer 22 and is substantially a co-extensive with the horizontal surface thereof. An upper sheet-metal plate 24 is located above the mica plate 23 and has dependent integral edge flanged portions 25 which interengage with depending flanges of the upper asbestos cloth layer 23. A plurality of sheet-metal screws 26 are employed to hold the upper sheet-metal plate in its proper operative position relative to the lower sheet-metal plate and extend through the two inter-engaging edge flanges of the plates, as well as through the depending edge-flange portions of the asbestos cloth 23.

As hereinbefore stated, a plurality of substantially parallel-extending helices are provided, one end of each of which is connected to a common bus bar 27 located adjacent to one end of the device. At the other end of the device and within the casing formed by the two sheet-metal plates, are provided three bus bars 28, 29 and 31, to which the other ends of the respective individual helices of wire are alternately connected. It is thus possible to selectively connect por-

tions of the entire heating element, comprising the plurality of helices through controlling device, such as switches, (not shown), to a suitable source of electric energy in order to vary the amount of energy translated in the wire, while still maintaining a substantially uniform distribution of heat from the surface of the device during the operation thereof.

10 The bus bars 28, 29 and 31 are secured in their proper operative positions by means of bolts 32, a plurality of nuts 33 being provided on each bolt to permit of securely clamping the bus bar in its proper operative position, as well as permitting the connection to the bolt of the ends of suitable supply-circuit conductors, not shown. An insulated wire 34 may be connected to one end of the bus bar 27 and to a common terminal member 35 located adjacent to the terminal bolts 32. A terminal box 36 may be employed to suitably protect the exposed terminal members, as hereinbefore described, and be mounted upon the underside of the 25 lower sheet-metal plate.

During the operation of the device which is usually employed to maintain candy at a predetermined temperature during the course of manufacture, the outer surface of the upper sheet-metal plate is covered by a 30 canvas cloth 37.

The cloth 37 is made large enough to provide integral edge-flange portions 38, the side flanges being provided with a plurality of metal eyelets 39 adapted to operatively engage studs 41 which are suitably secured against the side flange portions 25 of the metal plate 24, the object being to maintain the cloth tightly stretched. In 40 order to further assist in drawing the cloth cover 37 tightly over the surface of the upper sheet-metal plate, additional stretching and clamping means are provided and comprise metal bars 42, of substantially U-shape, 45 the inner ends of which are pivotally secured against the flanges 25 by rivet members 43 adjacent to the ends of the device. The construction is such that the member 42 may be raised to a substantially vertical position, 50 the cloth stretched adjacent to the ends as much as possible, after which the clamping member is moved to its normal operative position, whereby the cloth cover is stretched and then tightly clamped against the end 55 portion of the metal plate.

As this device is intended to be mounted in a substantially horizontal position, a plurality of angle bars 44 are secured against the under surface of the lower sheet-metal 60 plate, the distance therebetween being in accordance with the width of the table upon which the device is to rest.

The device embodying my invention thus provides a casing comprising two spaced 65 sheet-metal plates having interengaging

flange portions, a plurality of layers of heat-insulating and electric-insulating material located therein, and a plurality of substantially uniformly distributed resistor members, a plurality of layers of electric-insulating material being employed to insulate the heating element from the top sheet-metal plate. A removable cloth cover is provided with means for permitting it to be tightly stretched over the upper sheet-metal plate 75 from which it may be easily and quickly removed whenever required.

Various modifications and changes in detail and arrangement may be made without departing from the spirit and scope of the 80 invention, and such modifications are intended to be covered by the appended claims.

I claim as my invention:

1. In an electrical heating device, in combination, a sheet-metal plate having upturned edge flanges, a layer of heat-insulating material on said plate, a layer of flexible electrical-insulating material on said heat-insulating material, a resistor member located on and secured to said layer of electrical-insulating material, a layer of electrical-insulating material over said resistor and a superposed sheet-metal plate having downturned edge flanges operatively engaging the upturned edge flanges of said first 95 sheet-metal plate.

2. In an electrical heating device, in combination, a casing comprising a pair of spaced coextensive sheet-metal plates having laterally extending edge flanges operatively engaging each other, a layer of heat-insulating material on one of said plates, a heating element located thereon, a layer of flexible refractory electric-insulating material between said heating element and the 105 other of said plates, and means operatively engaging said edge flanges for holding said layer of heat-insulating material against said plate and for holding said plates in proper operative positions relatively to each other.

3. In an electrical heating device, in combination, a sheet-metal plate, a plurality of layers of electric-insulating and heat-insulating material located on said plate, a layer 115 of flexible refractory electric-insulating material on said layers of insulating material, means for securing said layer of flexible material against said layers of insulating material and a helically-wound resistor wire 120 secured to said flexible material.

4. In an electrical heating device, in combination, an upper and a lower sheet-metal plate having interengaging edge flanges, a layer of a heat-insulating material on said lower plate, a layer of electric-insulating material on said heat-insulating material, a heating element secured to said electric-insulating material, a layer of electric-insulating material between said upper sheet and 125

said heating element, and a cloth cover member removably associated with said upper sheet-metal plate.

5. In an electrical heating device, in combination, an upper and a lower sheet metal plate having interengaging edge flanges, a layer of a heat-insulating material on said lower plate, a layer of electric-insulating material on said heat-insulating material, a heating element secured to said electric-insulating material, a layer of electric-insulating material between said upper sheet and said heating element, a cloth cover member removably associated with said upper sheet metal plate, means for securing the side edges of said cover member to said upper sheet metal plate, and means for stretching the end portions of said cover member and for holding them tightly against the end flanges of said upper plate.
- 10 15 6. In an electrical heating device, in combination, an upper and a lower sheet metal

plate having interengaging edge flanges, a 20 layer of a heat-insulating material on said lower plate, a layer of electric-insulating material on said heat-insulating material, a heating element secured to said electric-insulating material, a layer of electric-insulating material between said upper sheet and said heating element, a cloth cover member removably associated with said upper sheet metal plate, means for securing the side edges of said cover member to said upper 25 sheet metal plate, and means for stretching the end portions of said cover member and for holding them tightly against the end flanges of said upper plate.

In testimony whereof, I have hereunto 30 subscribed my name this 27th day of November, 1922.

JAMES C. WOODSON.
